UNITED STATES PATENT OFFICE.

JOHN N. VAN METER, OF DELLVALE, KANSAS.

TOY FOR INFANTS.

1,279,615.

Specification of Letters Patent. Patented Sept. 24, 1918.

Application filed December 26, 1917. Serial No. 203,869.

To all whom it may concern:

Be it known that I, JOHN N. VAN METER, a citizen of the United States, residing at Dellvale, in the county of Norton and State of Kansas, have invented certain new and useful Improvements in Toys for Infants, of which the following is a specification, reference being had to the accompanying drawings.

10 This invention relates to toys, and particularly to toys in the nature of dolls or other figures.

15 The general object of my invention is to provide a toy of this character having a base which may be firmly attached to a high chair, a table, or any other suitable support, the toy being mounted upon the base by means of a spring which is freely movable in practically all directions and which 20 is preferably a coil spring, so that the child may strike the figure and thereby cause the figure to oscillate rapidly to the great amusement of the child, or may draw the figure over toward it by the flexibility of 25 the spring, the figure being provided with a teething ring, a pacifier or other suitable device of like character which the child may take into its mouth.

30 Other objects will appear in the course of the following description.

My invention is illustrated in the accompanying drawing, wherein:—

35 Figure 1 is an elevation partly in section of my improved toy showing it applied to a support, the support being in section;

Fig. 2 is a section on the line 2—2 of Fig. 1;

40 Fig. 3 is an elevation of the upper end of the toy, showing a teething ring applied thereto.

Referring to these figures, it will be seen that my improved figure toy comprises a clamp 10 having a lower jaw 11 and an upper jaw 12, the upper jaw being deflected 45 so as to extend laterally and then downward, and then laterally and rest flat against a table or other support. Through the lower jaw 12 passes a binding screw 13.

Extending upward from the jaw 12 is a 50 spring 14, which may be a round spring like a piece of highly tensioned spring wire or is preferably a coiled contractile spring. Mounted upon the extremity of this spring is a doll 15 or other figure. I do not wish 55 to be limited to the style of this figure, as it

may be in the form of a Teddy bear, or any other animal, but I have illustrated a doll. Whatever this figure is, it is preferably provided upon its head with a member 16 which 60 may be either in the form of an ordinary pacifier or in the form of a teething ring, the teething ring being designated 17 and the pacifier 18.

The clamp permits the device to be attached to a table, as for instance the table A of a high chair, the offset portion of the upper jaw permitting the clamp to be placed over the usual rail around the edge of the table. The child can keep itself amused by 70 striking or hitting the doll which will cause it to oscillate back and forth or from side to side in any direction, thereby amusing the infant. Furthermore, if the support be made of a stiff coil spring, the spring will 75 not only vibrate freely in all directions when the doll is struck or pulled and released, but the spring may be also expanded by drawing upon the doll so that the child can easily get the teething ring or pacifier 80 in its mouth and then upon release of the doll, the doll will swing back to its initial position and vibrate as before described. As before stated, I do not wish to limit myself to any of the details as to the form of 85 doll or figure nor to the specific form of pacifier or teething ring or other like member, nor to the specific form of the clamp, except as stated in the appended claims. Thus, for instance, the buttons on the doll 90 may be in the form of bells or rattles to render the figure more attractive and interesting to a child.

Having described my invention, what I claim is:—

1. A toy of the character described comprising a clamp, a spring extending from the clamp, and oscillatable freely in all directions, and a figure mounted upon the spring to oscillate therewith.

2. A toy of the character described comprising a base, a coil spring extending upward from the base, said spring being expandable and oscillatable in all directions, and a figure mounted upon the spring.

3. A toy of the character described comprising a clamp, a spring support extending upward from the clamp, a figure mounted upon said support to oscillate therewith, and a member mounted upon the figure for 110 insertion in the mouth of a child.

4. A toy of the character described comprising a clamp including opposed jaws and a screw passing through one of the jaws, a spring extending upward from the other jaw and freely oscillatable in a plurality of directions, and a figure carried upon the spring and oscillatable therewith.

5. A toy of the character described comprising a spring, a supporting and attaching means disposed at the lower end of the

spring, the spring being oscillatable freely in all directions, and a figure mounted upon the spring to oscillate therewith.

In testimony whereof I hereunto affix my signature in the presence of two witnesses. 15

JOHN N. VAN METER.
